UNITED STATES PATENT OFFICE.

BARTON S. SNOW, OF BATAVIA, ILLINOIS, ASSIGNOR TO T. W. SNOW CONSTRUCTION CO., OF CHICAGO, ILLINOIS, A CORPORATION OF ILLINOIS.

HOISTING MECHANISM.

Application filed March 18, 1921. Serial No. 453,421.

To all whom it may concern:

Be it known I, BARTON S. SNOW, a citizen of the United States, residing at Batavia, in the county of Kane and State of Illinois, 5 have invented a new and useful Improvement in Hoisting Mechanism, of which the following is a specification.

My invention relates generally to improvements in hoisting mechanisms employing a cable through the medium of which the load to be elevated is operated, and more particularly to hoisting mechanism provided for elevating coal from one level into a storage bin at a higher level from 10 which the coal is to be permitted to discharge, under the control of an operator, into the tenders of locomotives, these hoisting mechanisms commonly being formed of a drum upon which the cable is wound, with 15 the opposite end of the cable connected with a pair of oppositely moving hoisting buckets where two buckets are employed, or with a bucket and a counterweight where one bucket is employed, the counterweight usually being 20 of a weight equal to substantially one-half the weight of the bucket and the material carried thereby, so that the hoist operates at all times against the resistance of a weight tending to rotate the hoist drum 25 reversely.

In hoisting mechanisms of the general character above referred to, it is common practice to provide means whereby in the event of the reversing of the direction of 30 rotation of the drum by the load, as for example where the power for operating the drum is shut off, or through accident, as by breaking of parts, the drum becomes free to reversely rotate, the drum will be subjected 35 to a braking action which will hold it against such reverse movement; and it is one of my objects to provide a hoisting mechanism involving such means, which will be simple and economical of manufacture, 40 and operate positively in the case of the reversal of the rotation of the drum by the action of the load when rotating in either direction. Also hoisting mechanisms of the 45 general type, and more particularly of the kind referred to for the specific purpose above stated, viz., that in connection with 50 coaling stations, are usually provided in what are termed "hoist houses", the hoisting mechanism being provided with a gypsy or 55 niggerhead through the medium of which

the coaling cars are caused to be moved into a position wherein they dump coal to be elevated, into the lower bin from which latter it discharges into the hoisting buckets. It is necessary in practice that the hoist 60 house be so located relative to the elevating apparatus operated by the hoisting mechanism, that the hoisting drum will line up properly with the mechanism with which it cooperates, it being necessary in some 65 cases to position the hoist house at one side of the buckets, and in other cases to place the hoist house at the opposite side of the bucket apparatus, depending upon the particular conditions presented, it being required that 70 the niggerhead in either case be located adjacent the coaling track. The conditions presented by coaling stations, as commonly provided, are such, particularly because of the relatively small space between the coaling track and the service track upon which the tenders to be filled with coal from the upper storage bin, run, that as hoist mechanisms have hitherto been provided it has been necessary to provide different 75 constructions of hoist mechanism depending upon which side of the bucket-mechanism they are required to be placed, in order to properly line up the drum with the bucket apparatus and to have the nig- 80 gerhead adjacent the coaling track. One of my objects has to do with this general situation, it being my purpose to provide a construction of hoisting mechanism which may, by repositioning of its part, with the 85 minimum disassembling thereof, be suitable for location in the proper working position, at either side of the bucket apparatus, thereby permitting it to be installed at either side thereof or changed from one side 90 to the other, as desired.

Referring to the accompanying drawings:

Figure 1 is a plan view of my improved hoisting mechanism, with the hoisting cable omitted. Figure 2 is a view in side elevation 100 of the same. Figure 3 is an end view thereof, the machine being shown as viewed from the left hand side of Fig. 1; and Figure 4, a section taken at the line 4 on Fig. 2 and viewed in the direction of the arrow.

The frame of the machine involves a rigid base-frame 4 having a lateral extension 5 at one end thereof and provided at opposite sides with upright frames 6 affording journal support for a drum shaft 7, one end of 110

this shaft extending laterally beyond the frame 4 and carrying a niggerhead 8 as is usual in hoisting mechanisms. Rotatably mounted on the shaft 7 is a hoisting drum 9 as is commonly employed, the shaft 7 being provided with a clutch device 10 which may be of common construction and operated through the medium of a hand lever 11 for releasably clutching the drum 9 to the shaft 7, the drum 9 being provided with a series of clutch lugs 12 grouped about the shaft 7 and extending lengthwise thereof, which are adapted to intermesh with clutch lugs 13 on the clutch 10. The clutch lever 11 is pivoted at 11^a to a bracket 11^b secured to the adjacent upright by a bolt 11^c. The shaft 7 has rigidly secured thereto a worm wheel 14 which meshes with a worm 15 shown as extending horizontally with its axis at a right angle to the axis of the shaft 7. The worm 15 is rigidly secured to a shaft 16 journaled in spaced-apart boxes 17 connected with the adjacent one of the uprights 6 and in a box 18 rising from the frame 4 adjacent the extension 5, the box 18 being secured to the base by bolts 18^a extending through holes in the base. The shaft 16 is shown as provided with clutch mechanism 200 which may be of common construction, operated through the medium of a lever 20 fixed on a shaft 21 journaled in the frames 6, this clutch being provided for clutching to the shaft 16, at the will of the operator a belt pulley 22 journaled on the shaft 16 as for a purpose hereinafter stated. In the arrangement shown the shaft 21 carries two sleeves 46 rigidly secured thereto and provided with arms 46^a which are pivoted at their ends to the ends of links 45 through the medium of which the sliding clutch-part 50 is operated. The shaft 16 is also provided with a gear 23 rigid thereon which meshes with a pinion 24 rigidly secured to an armature shaft 25 of an electric motor represented at 26 and which, when the drum is to be reversely rotated against the action of a load, as hereinbefore mentioned, is provided of the reversible type. It will be understood from the foregoing that the drive for the drum 9 is from the motor 26 through pinion 25, gear 24, shaft 16, worm 15, worm wheel 14, shaft 7 and clutch 10, the motor 26 operating to drive the drum 9 in a direction responsive to the direction of the rotation of the motor 26.

In the particular arrangement shown provision is made for automatically controlling the operation of the motor 26 to cause it to operate in one direction for rotating the drum 9 in one direction to raise the loaded bucket (not shown) to the point of dumping and lower the empty bucket (not shown) to the point of loading, where two buckets are employed and are operatively connected with the opposite ends of a single cable (not shown) wound about the drum 9 as is common practice, and thereupon reverse the rotation of the motor 26, following an interval of rest during which the filled bucket is dumped and the empty bucket is loaded, the motor being reversed to effect the reversing of the rotation of the drum 9 to raise the newly filled bucket and lower the bucket just emptied to automatically control the speed of movement of the buckets while passing through different portions of the paths they travel; and to automatically continue the cycle of operations described, until the operator shuts off the mechanisms. The mechanisms shown for this purpose which, however, are shown by way of example only, involve what are commonly known as machine-cam-limit switch mechanism represented generally at 27 and an electrical timing device for actuating the motor after each period of rest, represented at 100, the mechanism 27 being shown as mounted upon a board 28 supported from the base frame 4 by uprights 29 and 30 rising from the base frame, the board containing elongated openings 28^a through which and through openings in the uprights 29 and 30, bolts 28^b supporting the board 28, pass. As the switch mechanisms 27 and 100 referred to are of common construction and are commonly employed in hoisting mechanism for controlling the automatic reversal of a drum-driving motor, description thereof is rendered unnecessary. It may be stated, however, that the switch mechanisms 27 and 100 are operated from a shaft 31 journaled in brackets 32 projecting laterally from the board 28 and operating when this shaft is rotated throughout a certain number of degrees to throw the switches controlling the motor for reversing the operation of the latter, with the proper time interval between the stopping and the starting of the motor prior to each reversal thereof for maintaining the buckets at rest during the filling and the dumping thereof. In the particular arrangement shown the shaft 31 is driven from the drum 9, through the medium of a sprocket 33 rigid with the drum and connected, by a sprocket chain 36, with a sprocket 34 on a shaft 35 journaled in a bearing 35^a secured to the upright 30 of the machine, as by the bolt 35^b passing through holes in the bearing 35^a and in the upright 30, the shaft 35 being provided with a pinion 37 meshing with, and driving, a gear 38 rigid on the shaft 31. The ratios of the various driving elements between the drum 33 and the shaft 31 are such that the drum 9 will be caused to rotate in each direction the number of times necessary to produce the desired length of travel of the buckets, viz, from filling position to discharging position and vice versa. The pitch of the teeth of the worm wheel 14 and the worm 15, is such that while the drum is driven through these elements first

in one direction and then in the opposite direction, the resistance afforded by the worm to the turning thereof by the worm wheel, should a condition occur which would 5 cause the load being elevated by the drum, to exert an action on the latter tending to rotate it reversely, is sufficient to prevent rotation of the worm and thus the load will 10 hang in elevated position, the worm and worm wheel thus operating to automatically 15 brake the drum, regardless of the direction in which the load tends to rotate the drum.

One of the features of my improved construction consists in positioning the drum on the shaft 7 at a point midway between the portions of this shaft at which the latter engages the bearings in the frame 6, whereby the drum is caused to occupy a centralized position relative to the median line 20 of the frame whether the shaft 7 be in the position shown in the drawings, or reversed end for end, as hereinafter referred to.

As hereinbefore stated, the boxes 17 for 25 the shaft 16 are supported on one of the frame-members 6, and to cause these boxes to assume the proper position, whether this frame member is located at one side of the frame of the hoist, or at its other side (the 30 latter being the case where the parts of the mechanism are reversed as hereinafter described) I preferably form the frame member referred to as shown in Fig. 4, viz, by providing corresponding seating bosses 39 and 40 at opposite sides of the line connecting the bolt holes 41 at which the frame-member is secured to the base 4 of the machine, whereby the outer faces of the bosses 40 will be located from the median line of 35 the frame 4, with the parts of the mechanism assembled to the position shown in Fig. 1, the same distance as the outer faces of the bosses 39 from the median line of the frame 4, when the frame 6 referred to is used at 40 the opposite side of the frame, viz, when the parts of the structure shown are assembled in reverse position. The openings in these bosses and through which the bolts (not shown) for securing the boxes 17 in 45 place, extend, are represented at 6^a, the supporting frame 6 being preferably flanged at opposite sides, as indicated at 42 and 43, to serve as abutments for the adjacent edges of the boxes 17. Where it is desired that 50 the niggerhead 8 carried by the shaft 7, extend from the end of this shaft at the upper side of Fig. 1, the various parts of the mechanism described and illustrated would be assembled to the positions shown in the 55 drawings. Where, however, it is desired that the shaft 7 present the niggerhead thereon at the opposite side of the hoist, viz, at the lower portion of the structure in Fig. 1, and which involves the turning of 60 the shaft 7 end for end, the various parts

would be repositioned as follows, assuming that the reversal referred to is to be made after the hoist has been assembled to the position shown in the drawings; the shaft 7, together with the worm 14, sprocket 33, 70 drum 9, clutch mechanism 10 and operating lever 11, all in assembled condition with the shaft 7, the clutch 11 being disconnected at its pivot 11^a from the bracket 11^b, would be lifted out of the bearings provided by 75 the supporting frames 6, the upper portions of the bearings having been first removed and the shaft 7 then turned end for end and set into the bearings in the frames 6. The shaft 16 with the parts carried thereby is 80 then removed, in assembled condition with the journals 18 and 17 therefor (the bolts connecting the journal boxes 17 with the frame 6 and the bolts 18^a, having been removed) to the opposite side of the frame 85 4 to engage the worm 15 with the worm-wheel 14, the journal-box 18 being secured to the frame 4 at the openings 44 therein which are positioned at the same distance from the median line of the frame, as the 90 holes therein through which the bolts 18^a pass in the position of the box 18 as shown in the drawings, and the journal boxes 17 then secured to the outer surfaces of the bosses 39 of the frame 6 opposite the one to 95 which they were formerly secured. All of the supporting frames 6 may be alike, or they may be provided of two kinds, one like that shown in Fig. 4 to present oppositely-facing bosses 39 and 40, and the other unprovided with bosses. In the case where all of the frames 6 are provided with the bosses, the frames may be used interchangeably at either side of the hoist, but where one of the frames 6 is provided with the bosses 100 and the other is not, the supporting frames 6 will be transposed upon reversing the positions of the parts of the hoist as hereinbefore suggested, to cause the one of these frames provided with the bosses to extend 105 adjacent the new location of the worm 15 and thus present the bosses 39 for attachment thereto of the boxes 17. Following the end to end reversal of the shaft 7 as stated the bracket 11^b is removed and secured to the opposite frame 6 in position to have the clutch lever 11 pivotally connected therewith, both of these frames having similarly-located bolt-receiving holes for the bolts 11^c.

In the shifting of the shaft 16 to the new 115 location as suggested, the clutch-operating arms 45 would be disconnected, from the arms 46^a, and the sleeve portions 46 would be slid along the shaft 21 to a position adjacent the opposite end thereof and thereupon rigidly secured thereto, and reconnected with the arms 45 in the new location of the shaft 16. The motor 26, being lined up with the median line of the frame 4, 120

the shifting of the shaft 16 to its new location causes the gears 23 and 24 to intermesh.

It is necessary that the sprocket 33 in its 5 reversed position, be connected with the sprocket 34 and that the latter, through its pinion 37 drive the gear 38 and the shaft 31, and to do this the driving connections are transposed from the position shown in 10 the drawings to the opposite side of the median line of the base 4. Inasmuch as the switch-carrying board 28 is shown slightly out of line with the median line of the motor 26, provision is made for shifting the board 15 28 crosswise of the hoist, this being possible by reason of the provision of the slots 28^a. In the reversing of the parts as stated, it is preferred that the gear 38 be removed from the shaft 31 and the bearing 35^a disconnected 20 from the support 30, the gear 38 being applied to the opposite end of the shaft 31 and the bearing 35 being shifted to the upright 29, which latter contains a hole (not shown) for the bolt 35^a so positioned that 25 the bearing 35^a will extend at the same distance from the median line of the base 4 as it does in the position shown in the drawings. In this position the parts of the gears 38 and 37 mesh and the sprocket 34 30 is lined up with the sprocket 33 for receiving the driving sprocket chain 36. It will therefore be understood that by forming the hoist of the parts as stated, the hoist may be provided as either a right or left hand 35 hoist, which is not only of advantage in the initial constructing of the hoist, as the same parts are used whether it be a right or left hand hoist, but is also of advantage when it becomes desirable to change the hoist from 40 a left hand to a right hand hoist or vice versa, on the job, such change not necessitating any substitution of parts, but merely the transposing of certain parts. In this connection it will be noted that the shaft 7 45 and the parts carried thereby are reversible end for end, as a unit, the drum 9 being lined up with the median line of the frame 4 in either position of the shaft 7, thereby rendering unnecessary the lateral shifting 50 of the frame 4 to line up the drum 9 with the bucket mechanism.

The shaft 16 is provided with the belt pulley and clutch described to adapt the machine to the driving of another mechanism, if desired, as for example an air-compressor often used in coaling-station installations, the clutch 200 controlling the connection of the belt pulley to the shaft 16, and when the mechanism is used for the purpose just 60 stated, the clutch 10 would be moved to a position to unclutch the drum 9 from the shaft 7.

It will be understood that, if desired, the switch mechanism 27 may be so constructed 65 and positioned that shifting of the latter is

not necessary in the transposing of the parts as described.

The feature of driving the mechanism 27 from the drum 9 instead of directly from the shaft 7 is of advantage as thereby the 70 proper timed relation of the drum and the mechanism 27 is maintained.

While I have illustrated and described a particular construction embodying my invention, I do not wish to be understood as 75 intending to limit it thereto as the same may be variously modified and altered without departing from the spirit of my invention.

What I claim as new, and desire to secure by Letters Patent, is:

1. In a hoist, the combination of a frame having bearings spaced apart, a shaft mounted in said bearings and provided with a gypsy, a drum on said shaft, an element on said shaft through the medium of which 85 said shaft is rotated, said shaft, drum and element being reversible, end for end, as a unit, and said drum being located midway of said bearings in either position of said shaft.

2. In a hoist, the combination of a frame having bearings spaced apart, a shaft mounted in said bearings, a drum rotatably mounted on said shaft, an element operatively connected with said shaft through the medium 95 of which the latter is rotated, clutch mechanism on said shaft for clutching said drum to said shaft, said shaft, drum element and clutch mechanism being reversible, end for end, as a unit, and said drum being located 100 midway of said bearings in either position of said shaft.

3. In a hoist, the combination of a frame having bearings spaced apart, a shaft mounted in said bearings, a drum on said shaft, a 105 worm wheel on said shaft through the medium of which the latter is rotated, said shaft, drum and worm wheel being reversible, end for end, as a unit, and said drum being located midway of said bearings in 110 either position of said shaft.

4. In a hoist, the combination of a base provided with uprights at opposite sides thereof affording bearings spaced apart, a shaft mounted in said bearings, a drum on 115 said shaft, an element on said shaft through the medium of which the latter is rotated, and means engaging said element for rotating said shaft and including a bearing structure supported on one of said uprights, said 120 upright being of the same form and size at the portions thereof on opposite sides of its median line, whereby when said bearing structure is secured to said upright when the latter is at either side of the base said bearing structure will extend at the same distance from the median line of the base.

5. In a hoist, the combination of a frame having bearings spaced apart, a shaft mounted on said bearings, a drum on said

shaft, an element on said shaft through the medium of which said shaft is rotated, said shaft, drum and element being reversible, end for end, as a unit, driving means for 5 said shaft engaging said element and comprising a driven shaft operatively in engagement with said element and adapted to be driven, said driven shaft being journaled on the frame of the hoist, said shaft and 10 the bearings therefor being adapted to be transposed to the opposite side of said frame to position it in operative relation to said element on said first-referred-to shaft, and to the power device, in the end to end reversed position of said first-referred-to shaft.

6. In a hoist, the combination of a frame having bearings spaced apart, a shaft mounted in said bearings, a drum on said 20 shaft, an element on said shaft through the medium of which the latter is rotated, said shaft, drum and element being reversible, end for end, as a unit, and said drum being located midway of said bearings in either 25 position of said shaft, a power device, the shaft of which is in line with a point midway between the sides of said drum, a driven shaft journaled on said frame, means for driving said driven shaft from said power 30 device, and means for driving said drum-equipped shaft from said driven shaft, the bearings for said driven shaft being transposable to the opposite side of the machine 35 for properly positioning the driven shaft relative to said element on the first-referred-to shaft, and said power device, in the end to end reversed position of said first-referred-to shaft.

7. In a hoist, the combination of a frame 40 having bearings spaced apart, a shaft mounted in said bearings, a drum on said shaft, an element on said shaft at one side of the center of the drum and through the medium of which said shaft is rotated, certain of said parts being transposable for 45 causing said element to extend at the opposite side of the center of the drum, a form device, the shaft of which is in line with a point midway between said journals, a driven shaft journaled on said frame, a gear 50 on said driven shaft, a gear on said power device meshing with the gear on said driven shaft, and means for driving said drum-equipped shaft from said driven shaft, the 55 journals for said driven shaft being transposable to the opposite side of the machine for properly positioning the driven shaft relative to said element and meshing the gear on said form device with the gear on 60 said drum shaft in the transposed position of said element on said first-named shaft.

8. In a hoist, the combination of a frame

having bearings spaced apart, a shaft mounted in said bearings, a drum on said shaft, an element on said shaft through the medium of which the latter is rotated, said shaft, drum and element being reversible, end for end, as a unit, and said drum being located midway between the sides of said drum, a driven shaft journaled on said frame, a gear on said driven shaft, a gear on said power device meshing with the gear on said driven shaft, and means for driving said drum-equipped shaft from said driven shaft, the bearings for said driven shaft being transposable to the opposite side of the machine for properly positioning the driven shaft relative to said element on the first-referred-to shaft, and said power device, in the end to end reversed position of said first-referred-to shaft.

9. In a hoisting mechanism, the combination of a shaft, a drum rotatably mounted thereon, means releasably connecting together said drum and shaft, a reversible power device for driving said shaft in opposite directions, and means, operated by said drum, operating automatically to control the movement of said power device in opposite directions, said mechanism being adapted for transmitting power for a plurality of purposes including as one purpose the driving of said drum, and said power device being operable in one direction when said drum is disconnected from said shaft.

10. In a hoisting mechanism, the combination of a shaft, a drum rotatably mounted thereon, means releasably connecting together said drum and shaft, an electrical reversible power-device for driving said shaft in opposite directions, and means, operated by said drum, operating automatically to control the movement of said power device in opposite directions, said mechanism being adapted for transmitting power for a plurality of purposes including as one purpose the driving of said drum, and said power device being operable in one direction when said drum is disconnected from said shaft.

11. In a hoisting mechanism, the combination of a shaft, a drum rotatably mounted thereon, means releasably connecting together said drum and shaft, a reversible electric motor for driving said shaft in opposite directions, and switch mechanism operated by said drum operating automatically to control the movement of said motor in opposite directions, said mechanism being adapted for transmitting power for a plurality of purposes including as one purpose the driving of said drum, and said power device being operable in one direction when said drum is disconnected from said shaft.

BARTON S. SNOW.
